UNITED STATES PATENT OFFICE.

BERT G. LARRABEE, HARRY A. ROOT, AND ERNEST S. CASSADAY, OF HOUSTON, TEXAS, ASSIGNORS TO PORTABLE SELF-SERVING STORE COMPANY, OF HOUSTON, TEXAS, A CORPORATION OF DELAWARE.

DESIGN FOR A VENDING-MACHINE CASING.

Application filed February 13, 1928. Serial No. 25,436. Term of patent 3½ years.

To all whom it may concern:

Be it known that we, BERT G. LARRABEE, HARRY A. Root, and ERNEST S. CASSADAY, citizens of the United States, residing at Houston, in the county of Harris and State of Texas, have invented a new, original, and ornamental Design for a Vending-Machine Casing, reference being had to the accompanying drawing, forming a part hereof.

Fig. 1 of the drawing is a front elevation of a vending machine casing showing our new design; and Fig. 2, a side elevation thereof.

We claim:

The ornamental design for a vending machine casing, as shown.

In testimony whereof, we hereunto affix our signatures.

BERT G. LARRABEE.
HARRY A. ROOT.
ERNEST S. CASSADAY.
